UNITED STATES PATENT OFFICE

132,669

DESIGN FOR A SIGN

A. C. Frisbie, Jr., Kansas City, Mo.

Application March 23, 1942, Serial No. 106,287

Term of patent 7 years

To all whom it may concern:

Be it known that I, A. C. Frisbie, Jr., a citizen of the United States, residing at Kansas City, in the county of Jackson and State of Missouri, have invented a new, original, and ornamental Design for a Sign, of which the following is a specification, reference being had to the accompanying drawing, forming a part thereof.

Fig. 1 is a front elevational view of the sign, showing my new design.

Fig. 2 is an edge elevational view thereof; and Fig. 3 is a top plan view thereof.

I claim:

The ornamental design for a sign, as shown.

A. C. FRISBIE, JR.
